CLAIM

The ornamental design for a funnel for simultaneous mixing and dispensing of gasoline and oil for use in internal combustion engines, as shown and described.

DESCRIPTION

FIG. 1 is a front elevational view of a funnel for simultaneous mixing and dispensing of gasoline and oil for use in internal combustion engines;

FIG. 2 is a top plan view thereof;

FIG. 3 is a bottom plan view thereof;

FIG. 4 is a right side elevational view thereof, the left side being a mirror image of that shown;

FIG. 5 is a rear elevational view thereof; and

FIG. 6 is a top, rear and right side perspective view thereof.
